UNITED STATES PATENT OFFICE.

STEPHEN LOUIS GARTLAN, OF TORONTO, ONTARIO, CANADA, ASSIGNEE OF FIFTY-FIVE
ONE-HUNDREDTHS TO ALBERT EDWARD COODERHAM, OF TORONTO, CANADA.

PROCESS FOR TREATING HYDROCARBONS.

Application filed October 28, 1921, Serial No. 511,041. Renewed January 8, 1923.

To all whom it may concern:

Be it known that I, STEPHEN LOUIS GARTLAN, a citizen of the United States of America, residing at the city of Toronto, in the county of York and Province of Ontario, Dominion of Canada, have invented certain new and useful Processes for Treating Hydrocarbons; and I hereby declare that the following is a full, clear, and exact description of the same.

It is known that a natural telluric hydrocarbon is a mixture of substances of varying boiling points, and that each of the hydrocarbons of higher boiling points contained in such mixtures is, during the process of distillation, exposed to various degrees of temperature below its own boiling point, so long as the hydrocarbons of lower boiling points are not removed from the still, and that the separation of these hydrocarbons by distillation is often difficult for fractions boiling as low as 200° C., on account of the ease of partial decomposition of the higher boiling fractions at ordinary atmospheric pressure.

It is also known in the cracking of heavy oils, that two essential factors govern, largely, the reactions that take place, namely temperature and pressure, the function of increased temperature being to break the bonds of groups that make up the complex hydrocarbon molecule, and the function of pressure, which is of chief importance, being to exert an influence on the nature of the resulting product.

Broadly speaking, cracking processes have heretofore been divided into two principal types; those that involve cracking at atmospheric pressure and those that involve cracking under increased pressure.

The disadvantage of processes involving cracking at atmospheric pressure is the formation of relatively large volumes of olefins and the tendency of the hydrocarbons to pass out of the reacting sphere with a small degree of alteration; and the difficulty of obtaining cracking in any effective degree in processes operating without pressure, is that the higher temperatures cannot be attained without causing vaporization and without pressure the vapors cannot be held in the heated zone. The degree of conversion is necessarily less at atmospheric pressure than under high pressure, as on account of the

greater stability of the lighter molecules 55 only the heavier molecules are subject to alteration.

Great danger is inherent in cracking operations in which a large volume of liquid is heated under pressure in a still or other 60 large container, as a liquid-vapor phase system necessitates the employment of a given pressure for a given temperature and vice versa, unless one of the phases be caused to disappear. Therefore, in order to reach the 65 high temperatures that are desirable in order to bring about a maximum of cracking it is necessary to use correspondingly high pressures if the two phase system is to be maintained. This simultaneous use of both 70 high temperatures and high pressures in the same vessel is a source of danger when a large volume of liquid is heated in a single operation, as the container is apt to give way and the great volume of highly heated 75 liquid then becomes a serious menace.

Processes of the above nature are also subject to the limitation common to all two phase systems namely, that the temperature and pressure cannot be varied independently 80 of each other. This fixed interdependence of temperature and pressure has heretofore been one of the greatest handicaps of all two phase systems, for the higher temperatures and pressures, favorable for cracking 85 the lighter and intermediate fractions, cannot be attained in large operations because of the difficulty of finding retainers that will withstand the necessary strain.

By conducting the vaporization at approximately atmospheric pressure and continuously withdrawing the vapors from the vaporizing zone, a continuous evolution of the vapors can be maintained at temperatures which will permit of the vapors passing from 90 the vaporizing zone with but a minimum alteration of the original hydrocarbon molecules, and then by bringing these vapors to a favorable temperature, the cracking operation can be carried on in a separate apparatus with maximum efficiency under controllable conditions of temperature, pressure 100 and subsequent release of pressure for the sudden expansion of the compressed vapors, and will insure substantially all of the 105 evolved vapors being broken down into the desired product.

To this end the vaporizing and cracking

operations are divided into distinct but interdependent stages and the temperature and pressure employed during the vaporizing stage are varied independently of the 5 temperature and pressure employed during the cracking stage, and in a two phase system, necessitating the employment of pressure and temperature, the pressure may be caused to entirely disappear during the 10 vaporizing stage. As a consequence, a large volume of liquid may be heated and the maximum vaporization may be attained in a single operation without danger of the container giving way, and without danger 15 of the large volume of highly heated liquid becoming a serious menace. And further the temperature and pressure during the vaporizing stage can be so controlled that the evolved vapors will pass from the vaporizing zone with but a minimum alteration 20 of the bonds of groups that make up the original hydrocarbon molecules and the vaporization, under these conditions, may be continued until an excessively low pressure 25 in the vaporizer indicates that the maximum vaporization has been attained. These vapors after passing from the vaporizing zone, can be brought to a temperature favorable to their alteration during the second or 30 cracking stage by increasing and maintaining the temperature attained during the vaporization, either before or during the period when the cracking pressure is exerted on them, and the pressure during the cracking 35 stage may be varied to meet the requirements of the reaction and afterwards released for the sudden expansion of the compressed vapors. This regulation of the temperatures and pressures employed during 40 the vaporizing and cracking stages gives control to a large extent, of the nature of the resulting product and the percentage of the original hydrocarbon treated which can be converted into the resulting product. 45 This invention therefore, relates to a process or method consisting of distinct, but interdependent stages by which the vaporization of hydrocarbons, particularly teluric hydrocarbons, and the alteration of the 50 original hydrocarbon molecules to form resulting products of different specific gravity and boiling points to the hydrocarbon vaporized may be continuously carried on in safety and with maximum efficiency, and it consists 55 essentially of:—conducting the vaporization under favorable conditions of temperature at atmospheric, or plus or minus atmospheric pressure, the degree of variation in either direction from zero being negligible 60 and the heat applied during the vaporizing period being so regulated as to maintain a continuous evolution of vapors without appreciably altering the bonds of groups that make up the original hydrocarbon 65 molecules; withdrawing the evolved vapors

from the vaporizing zone during the vaporizing period; increasing and maintaining the temperature of the vapors attained during the vaporization to a degree favorable to the cracking stage of the operation; compressing the vapors under controllable conditions of temperature and pressure and releasing the pressure after compression for their sudden expansion and the alteration 75 of the original hydrocarbons into liquefied resulting products of different specific gravity and boiling points to the hydrocarbon treated.

The objects of the invention are:—to enable the vaporization to be carried on at relatively low temperatures, and under such conditions of pressure as will facilitate the rapid evolution of the vapors with but slight alteration of the original hydrocarbon molecules; to effect the alteration of 80 these molecules by a controllable regulation of temperature and pressure, followed by release of pressure and sudden expansion to form a resulting product of a different specific gravity and boiling points to the hydrocarbon treated; and to eliminate the element 85 of danger resulting from high pressures within the vaporizing sphere and the element of failure of the apparatus resulting 90 from high pressures during the vaporization.

In carrying out these objects a suitable vaporizing apparatus is employed in which a large volume of hydrocarbon matter can be exposed to heat. A steam generator may be connected with the vaporizing apparatus for the injection of steam into the hydrocarbon or hydrocarbon vapors during the vaporizing period to increase the degree 100 and rate of vaporization. A superheater 105 may be connected with the vaporizing apparatus to raise the temperature of the vapors to a degree favorable to the cracking stage of the operation. A compressor, suitably jacketed for heating and cooling 110 purposes, is connected directly with the vaporizing apparatus and with the superheater for continuously withdrawing the evolved vapors from and maintaining a diminished pressure within the vaporizing 115 zone and superheater and compressing the vapors under conditions of heat exchange favorable to the requirements of the reaction, and an expansion chamber is connected with the compressor for releasing the pressure after compression for the sudden expansion of the vapors.

In a series of tests conducted according to this invention kerosene fractions have been vaporized by boiling the mass at temperatures ranging from 160° C. to 300° C. and heavy Mexican crude petroleum hydrocarbons have been vaporized by boiling the mass at temperatures ranging from 98° C. to 415° C. and the vapors have been al- 130

tered into other hydrocarbon fractions with a compressor operating at pressures up to 1500 pounds, and at temperatures up to 550° C. during the compression, the pressure after compression being released for the sudden expansion of the vapors.

The drawing is a diagrammatic view of a suitable arrangement of apparatus by which the operation may be effectively carried out.

In the practical operation of the invention it has been found that the following method and apparatus produce satisfactory results both as regards yields of the desired hydrocarbon products and economy of operation, but other apparatus of any usual or approved type may be substituted for that hereinafter described and the specific temperatures and pressures may be varied to the character or conditions of the hydrocarbons treated.

The plant in which this process was elaborated consists of a 50 H. P. tubular type boiler 8 for steam generating purposes connected:—to an engine 16 which drives the compressor 5; to the steam coil 3 of the superheater 2; and to the outer jacket of the compressor 5. The superheater 2 is an oil fire heated box of brick construction containing two sets of coils 3 and 4 for superheating the steam from the boiler, and the vapor from the still or vaporizer.

The superheater is provided with a burner or burners 25 connected with a fuel supply by a pipe 26, and these burners are supplied with a steam jet from the steam pipe line 15.

The vaporizer 1 is of cylindrical construction of a total volume of approximately 100 gallons and is provided with temperature and pressure recording instruments. Connected with it is one of the steam lines from the superheater and two vapor lines, one of the vapor lines leading through the superheater to the compressor. The compressor, provided with temperature and pressure recording instruments, is of the three stage type, having an outer jacket such as is commonly used for cooling purposes, and has a capacity of twelve cubic feet per minute, at 110 R. P. M. The compressor is connected with the intake 18 of the expansion chamber 17, through a needle valve 19, and both compressor and expansion chamber are capable of withstanding high pressures. The expansion chamber 17 consists of a steel cylinder with a total volume of about 2½ cubic feet and is capable of withstanding high pressures up to approximately 2,000 pounds. The cooler 21 is of the usual spiral type consisting of about thirty feet of one and one quarter inch coiled pipe and the receiving tank 23 is of thirty gallon capacity and capable of withstanding pressures up to 300 pounds.

The liquid hydrocarbons to be treated are

introduced into the vaporizer 1 which is provided with burners 12 connected by a pipe line 13 with the source of fuel supply and when oil is used as fuel the burners are also connected by a pipe line 15 with the steam coils 3 of the superheater 2, the steam flowing through the pipe line 15 to the burners atomizing the oil and spraying it, under pressure, through the burner outlets. The vaporizer 1 takes the form of a cylindrical still, but it may take the form of an apparatus of any other design which will provide for the continuous evolution of a relatively large volume of vapors and may be charged and run in batches or a number of them may be connected with one or more compressors, and run simultaneously, or a number of them may be connected in series and run simultaneously, the oil circulating in the latter case from one to another of the series; or it may take the form of a tube or set of tubes of similar vaporizing capacity, and in an apparatus of tubular construction, satisfactory results may be obtained by continuously injecting the oil into the tube or series of tubes suitably heated to continuously evolve vapor.

In the construction shown in the drawings, the vaporizer is provided with two valve controlled vapor pipes 6 and 7 leading from the vaporizing zone, the valve controlled pipe 6 directly connecting the vaporizer with the compressor at the usual intake port on the low pressure cylinder and conducting the vapors directly from the vaporizer to the compressor 5, and the valve controlled pipe 7 conducting the vapors from the vaporizer to the coil 4 of the superheater 2, and then to the valve controlled pipe 6, between its valve 6' and the intake port of the compressor 5. To minimize the drop in temperature between the vaporizer or superheater and the compressor, the pipes 6 and 7 may be suitably covered with heat insulating material. The steam coil 3 in the superheater 2 is connected with the steam generator 8 and supplies superheated steam to the vaporizer through the steam pipe 10.

To facilitate the cracking of the vapors it is necessary to maintain the compressor at a temperature favorable to the maximum cracking efficiency. In treating Texas fuel oil the compressor was preheated to a temperature up to 550° C. and this temperature was maintained for the compressor during the evolution of the vapors of those fractions evolved by boiling the mass at temperatures between 124° C. and 400° C. When the temperature of the mass for the evolution of the vapors of the higher boiling fractions exceeded 400° C., it was found advisable to reduce the temperature of the compressor to about 450° C.

For the purpose of maintaining an effective operating temperature, the compressor

is provided with a coil or jacket for heating and cooling purposes. The intake end of this coil or jacket is connected with the main steam pipe line 9 by a valve controlled steam pipe 11, and with the steam coil 3 in the superheater 2 by a valve controlled pipe 15.

Steam circulates from the steam boiler through the valve controlled pipe 15 and superheater, to the jacket of the compressor 10 to externally preheat the compressor before the vapors are evolved in the vaporizer. In the treatment of the Texas fuel oil previously mentioned the compressor was maintained at a temperature of about 550° C. 15 during the compression of the hydrocarbon fractions when the boiling temperature of the mass was or below 400° C. When the boiling temperature of the mass attained 400° C., the steam from the superheater to 20 the coil or jacket of the compressor was cut off, and when the boiling temperature of the mass exceeded 400° C., the steam circulated from the steam generator by means of the pipe lines 9 and 11, to the compressor and 25 effected a heat exchange or reduction of temperature of the compressor to about 450° C., the temperature of the compressor at all times being controlled to the requirements of the cracking temperature of the vapors 30 being compressed. When it is necessary to effect a considerable reduction in the temperature of the compressor, suitable mechanical cooling means may be connected with the compressor for that purpose.

35 Connected with the intake 18 of the expansion chamber 17 and the exit of the high pressure cylinder of the compressor is a vapor line 20, and this high pressure vapor line is covered with suitable insulating material to minimize the drop in temperature. The expansion chamber is provided with a gauge glass so that the apparent condition and the rate of collection of the liquefied vapors may be observed. When the oil is 40 introduced into the vaporizer, steam pressure is raised in the steam generator to about 100 pounds and the burners in the superheater are lighted and so regulated as to superheat the steam from the generator and 45 the vapor passing from the vaporizer through the superheater to the compressor to a temperature up to 550° C. Steam from the superheating coil 3 is then conducted through the coil or jacket of the compressor 50 to preheat the compressor to approximately the same temperature. The burners in the vaporizer are now lighted and the temperature raised until vapors are evolved. The evolution of the vapors may be continued 55 until an excessively low pressure in the vaporizer indicates that the maximum vaporization of the oil introduced into the vaporizer has been attained. When the vapors begin to be evolved, the compressor is started 60 and the vapors are withdrawn by the com-

pressor from the vaporizer through the vapor coils 4 of the superheater. The temperature of the superheater is so regulated as to heat the vapors of the low boiling fractions, before compression, to a temperature 70 of about 550° C., which is found to be favorable to the cracking stage of the operation.

When the vapors passing through the superheater pick up sufficient heat to keep the compressor at the proper operating temperature, the superheated steam to the coil or jacket of the compressor is turned off. When the temperature of the hydrocarbons in the vaporizer reaches the maximum boiling point before cracking, the vapors are conducted 80 direct from the vaporizer to the compressor. When the temperature of the compressor exceeds 550° C. wet steam from the steam generator is turned into the coil or jacket through the pipes 9 and 11. The introduction of this wet steam into the coil or jacket of the compressor has the effect of reducing the temperature of the compressor, thereby preventing an abnormal rise in its temperature, due to the high temperature of the vapors of the higher boiling fractions and any heat developed by the compression.

Instead of using the superheater to preheat the vapors passing from the vaporizer to the compressor, the temperature of the compressor can be raised to a degree which will permit of the vapors passing direct from the vaporizing zone to the pressure zone at the vaporizing temperature and being heated by the compressor to the required degree for the cracking stage of the operation.

The temperature of the vaporizer is so regulated as to maintain a continuous evolution of the vapors and the speed of the compressor is so regulated as to continuously withdraw the vapors from the vaporizing zone and maintain in it a normal pressure at or about atmospheric pressure, the degree of variation from atmospheric pressure in either direction being negligible. The low pressure in the vaporizer facilitates the rapid evolution of the vapors; it enables the vaporization to be carried on at relatively 105 low temperatures; it eliminates the risk of danger resulting from high pressures within the vaporizing sphere; and it eliminates the danger of failure of the apparatus resulting from high pressures.

110 The vaporization of the liquid is started at a relatively low temperature to vaporize the hydrocarbon fractions of low boiling point ranges, each fraction as it is vaporized being drawn off from the vaporizer by the compressor, which action of the compressor maintains in the vaporizer a normal atmospheric pressure or pressure varying but little above or below atmospheric pressure.

115 When the vapors of the low boiling fractions have been evolved and withdrawn from

the vaporizer, the temperatures of the vaporizer and its contents are increased to continue the vaporization of the higher boiling fractions, the continuous withdrawal of these vapors being maintained by the compressor and the operation being continued until an excessively low pressure in the vaporizer indicates that the maximum vaporization has been attained.

10 When the vaporizing temperature reaches 200° C., superheated steam may be introduced into the vaporizer and the mixture of vapors and steam is drawn off by the compressor through the superheater. The pressure in the high pressure cylinder is regulated to the requirements of the cracking operation and may vary from 100 pounds to 1,500 pounds or more per square inch. When the temperature of the mass for the 20 evolution of the vapors reaches 400° C. the passage of the mixture of vapors and steam through the superheater may be discontinued and vapors may then be conducted directly to the compressor from the vaporizer.

25 The operation of the compressor is regulated to give any required pressure in the high pressure cylinder. A practically constant flow of compressed vapors is maintained through the needle valve into the expansion chamber where the pressure is immediately reduced to or within a few pounds of atmospheric pressure. During the compression the temperature of the vapors will approximate 550° C., and this temperature 30 and the pressure are maintained until the delivery of the vapors through the needle valve into the expansion chamber, where the vapors are suddenly expanded. The sudden expansion of the vapors causes a great drop 35

40 in temperature and the liquefaction of all but the very lightest vapors. The strain on the vapors caused by the high temperature and pressure in the compressor and the sudden expansion and great drop of pressure in 45 the expansion chamber results in the alteration of the bonds of groups that make up the original hydrocarbon molecules, and the formation of bonds of groups which make up hydrocarbon molecules of different specific 50 gravity and boiling points or, in other words, this arrangement of heat control, compression, and expansion, brings into use and renders possible the close control of the two well recognized factors made use of in the cracking 55 of hydrocarbons i. e. temperature and pressure, and brings into operation an additional factor, i. e., the principle of subjecting the hydrocarbon molecules to great strain by expansion.

60 For the condensation of those vapors not liquefied in the expansion chamber, the intake end of the cooler 21 is connected with the outlet 22 of the expansion chamber 17 and this cooler 21 discharges into the receiver 23 where all liquefied vapors are col-

lected, the differential pressure between the expansion chamber and receiving tank permitting of the unimpeded circulation of the liquefied products to the latter. In this way everything except some of the permanent 70 gases is collected in the receiving tank in the form of liquid of different boiling points and specific gravity to those of the original hydrocarbon treated.

It has been ascertained in the practical 75 operation of this method of treating hydrocarbon oils, such as heavy paraffin base or asphaltum base crude oils, that yields as high as 31% of gasoline have been obtained on a single run on the batch system. 80

It will be understood that the above mentioned temperatures and pressures have been merely set forth as one specific example of the practical application of the process and that they may be varied to meet the requirements of the operating conditions of a commercial plant. 85

Having thus fully described my invention, what I claim as new and desire to secure by Letters Patent is:—

90 1. A cracking process for the production of lower boiling liquid hydrocarbons which consists of transforming liquid hydrocarbon into vapors and while in a vapor state subjecting them to a plurality of intense 95 changes of pressure and then suddenly releasing the pressure.

2. A cracking process for the production of lower boiling liquid hydrocarbons which consists of, transforming liquid hydrocarbon into vapors, suddenly applying intense 100 compression on the vapors and suddenly releasing the compression after the pressure has been applied.

3. A cracking process for the production 105 of lower boiling liquid hydrocarbons which consists of transforming liquid hydrocarbon into vapors, transferring all the evolved vapors from the vaporizing zone to a pressure zone separate from the vaporizing zone, 110 and effecting the alteration of the evolved vapors into a lower boiling hydrocarbon by intensely compressing the transferred vapors and then suddenly expanding them, and collecting the products. 115

4. A cracking process for the production 120 of lower boiling liquid hydrocarbons which consists of separating the operation into distinct but interdependent stages and vaporizing the liquid hydrocarbon during one of the stages and maintaining a relatively low pressure in the vaporizing zone during the vaporization, and during another stage, separate from the vaporizing stage, transferring all the evolved vapors to a separate 125 pressure zone and altering these vapors into a lower boiling hydrocarbon by suddenly applying intense pressure and then suddenly releasing the pressure, and collecting the product. 130

5. A cracking process for the production of lower boiling liquid hydrocarbons which consists in evolving hydrocarbon vapors at low pressures, transferring all the vapors to a pressure zone separate from the vaporizing zone without a reduction of temperature of said vapors, altering the transferred vapors into a lower boiling hydrocarbon by applying a plurality of intense changes of pressure to said vapors, including the compression and sudden expansion of the vapors, and then collecting the altered product. 70
6. A cracking process for the production of lower boiling liquid hydrocarbons which consists of vaporizing liquid hydrocarbon, continuously transferring all the evolved vapors to a pressure zone separate from the vaporizing zone, and then altering them into a lower boiling hydrocarbon by suddenly applying intense pressure and suddenly releasing the pressure. 80
7. A cracking process for the production of lower boiling liquid hydrocarbons which consists of vaporizing liquid hydrocarbon at about atmospheric pressure, transferring all the evolved vapors to a pressure zone separate from the vaporizing zone, and then altering them into a lower boiling hydrocarbon by the sudden application of intense pressure followed by a sudden release of pressure. 90
8. A cracking process for the production of lower boiling liquid hydrocarbons which consists of vaporizing liquid hydrocarbon at relatively low temperatures, continuously transferring all the evolved vapors from the vaporizing zone to a pressure zone separate from the vaporizing zone and maintaining a low pressure in the latter, and then altering these vapors into a lower boiling hydrocarbon by suddenly applying intense pressure on the vapors and suddenly releasing the compression after the pressure has been applied. 100
9. A cracking process for the production of lower boiling liquid hydrocarbons which consists of vaporizing liquid hydrocarbon at about atmospheric pressure, maintaining a continuous evolution of vapor, continuously withdrawing the evolved vapors from the vaporizing zone during the vaporizing period and maintaining a substantially constant pressure in it, and then altering these vapors into a lower boiling hydrocarbon by a plurality of intense pressure changes followed by a sudden release of pressure. 110
10. A cracking process for the production of lower boiling liquid hydrocarbons which consists of vaporizing liquid hydrocarbon at about atmospheric pressure, maintaining a continuous evolution of vapor, continuously withdrawing the evolved vapors from the vaporizing zone during the vaporizing period and maintaining a substantially constant pressure in it, and then altering these
- vapors into a lower boiling hydrocarbon by a plurality of intense pressure changes, followed by a sudden release of pressure, and regulating the intensity of the pressure changes to the requirements of the operation. 70
11. A cracking process for the production of lower boiling liquid hydrocarbons which consists of vaporizing liquid hydrocarbon, maintaining a continuous evolution of vapors, continuously withdrawing the evolved vapors from the vaporizing zone during the vaporizing period and maintaining a substantially constant pressure in it, and then altering these vapors into a lower boiling hydrocarbon by the sudden application of intense pressure followed by a sudden release of pressure, and regulating the temperature during compression to the requirement of the operation. 75
12. A cracking process for the production of lower boiling liquid hydrocarbons which consists of vaporizing liquid hydrocarbon at about atmospheric pressure, maintaining a continuous evolution of vapor, continuously withdrawing the evolved vapors from the vaporizing zone during the vaporizing period and maintaining a substantially constant pressure in it, and then altering these vapors into a lower boiling hydrocarbon by the application of intense pressure followed by a sudden release of the pressure, and regulating the temperature and pressure during the compression to the requirements of the alteration. 85
13. The herein-described cracking process for the production of lower boiling liquid hydrocarbons which consists of vaporizing liquid hydrocarbon, transferring all the evolved vapors to a pressure zone separate from the vaporizing zone, and then altering these vapors into a lower boiling hydrocarbon by multiple stage compression followed by sudden expansion. 95
14. A cracking process for the production of lower boiling liquid hydrocarbons which consists of vaporizing liquid hydrocarbon, transferring all the evolved vapors from the vaporizing zone to a pressure zone separate from the vaporizing zone, regulating the heat in the pressure zone at will to a degree favorable to the operation, and then altering these vapors into a lower boiling hydrocarbon by intensely compressing the vapors and suddenly releasing the intense compression after the pressure has been applied. 105
15. A cracking process for the production of lower boiling liquid hydrocarbons which consists in vaporizing liquid hydrocarbon, transferring all the evolved vapors from the vaporizing zone to a pressure zone separate from the vaporizing zone, raising said vapors at will to a temperature higher than that at which they were evolved, subjecting the vapors to intense pressure ranging from 200 lbs. or less to 1500 lbs. or more per square 115
- 120
- 125
- 130

inch, and then expelling the compressed vapors from the pressure zone and suddenly releasing the pressure.

16. A cracking process for the production of lower boiling liquid hydrocarbons which consists in vaporizing liquid hydrocarbon, transferring all the evolved vapors from the vaporizing zone to a pressure zone separate from the vaporizing zone, raising said vapors at will to a temperature higher than that at which they were evolved, subjecting all the vapors to intense sudden pressure, increasing the pressure until the maximum pressure has been attained, and then expelling the compressed vapors from the pressure zone and suddenly releasing the pressure.

17. A cracking process for the production of lower boiling liquid hydrocarbons which consists of vaporizing liquid hydrocarbon at a relatively low temperature, continuously transferring all the evolved vapors from the vaporizing zone to a pressure zone separate from the vaporizing zone and maintaining a low pressure in the vaporizing zone, and then altering these vapors into a lower boiling hydrocarbon by suddenly applying intense pressure and suddenly releasing the compression after the maximum pressure has been applied.

18. A cracking process for the production of lower boiling liquid hydrocarbons which consist of vaporizing liquid hydrocarbon at a relatively low temperature and pressure, continuously transferring all the evolved vapors from the vaporizing zone to a pressure zone separate from the vaporizing zone and maintaining a low pressure in the vaporizing zone, and then altering these vapors into a lower boiling hydrocarbon by exerting on them sudden pressure of an intensity which will result when the pressure is released in the cracking of the vapors, suddenly releasing the compression after the maximum pressure has been applied, and varying the temperature and pressure employed during the vaporization independently of the pressure employed during the compression.

19. A cracking process for the production of a lower boiling liquid hydrocarbon which consists of vaporizing liquid hydrocarbon at a relatively low pressure, continuously transferring all the evolved vapors from the vaporizing zone to a pressure zone separate from the vaporizing zone and maintaining a low pressure in the vaporizing zone, then altering these vapors into a lower boiling hydrocarbon by compressing the vapors when transferred to the pressure zone and exerting on all the transferred vapors during the compression pressure of an intensity which will result in a lower boiling hydrocarbon when the pressure is released, expelling the compressed vapors from the pressure zone after the pressure

has been applied, and suddenly expanding the intensely compressed vapors.

20. A cracking process for the production of lower boiling liquid hydrocarbons which comprises converting liquid hydrocarbon into vapor, transferring all the vapors to a separate pressure zone, regulating the temperature of the transferred vapors at will, compressing all the transferred vapors by the sudden application of intense pressure, releasing the pressure by sudden expansion of the vapors, and collecting the product.

21. A cracking process for the production of lower boiling liquid hydrocarbons which comprises converting liquid hydrocarbon into vapor, transferring all the vapors to a separate pressure zone, regulating the temperature of the transferred vapors at will, compressing all the transferred vapors by the sudden application of intense pressure ranging from 200 pounds or less to 1500 pounds or more per square inch, releasing the pressure by the sudden expansion of the vapors, and collecting the product.

22. A cracking process for the production of lower boiling liquid hydrocarbons which consists of transforming liquid hydrocarbon into vapors, transferring all the evolved vapors from the vaporizing zone to a pressure zone separate from the vaporizing zone, without a lowering of the temperature attained during the vaporization, and then altering the transferred vapors by a plurality of intense sudden pressure changes followed by a sudden release of pressure.

23. A cracking process for the production of lower boiling liquid hydrocarbons which comprises converting liquid hydrocarbon into vapors, transferring all the vapors to a separate pressure zone, compressing all the transferred vapors by the sudden application of intense pressure, releasing the pressure by sudden expansion of the vapors and injecting steam into the hydrocarbon matter being vaporized or into the evolved vapors before the maximum pressure is applied.

24. The herein-described cracking process for the production of lower boiling hydrocarbons which consists of vaporizing the hydrocarbon mass at about atmospheric pressure, regulating the heat for the vaporization to maintain a continuous evolution of vapors, maintaining a relatively low pressure in the vaporizing zone continuously during the vaporizing period, varying only slightly above or below atmospheric pressure, regulating the temperature of the vapors evolved during the vaporization to a degree favorable to the cracking stage of the operation, compressing all the vapors and releasing the pressure after compression for the sudden expansion of the vapors to form a resulting product differing in specific gravity and boiling points from the hydrocarbon vaporized.

25. The herein-described cracking process for the production of lower boiling hydrocarbons which consists of vaporizing the hydrocarbon mass at about atmospheric pressure, and regulating the temperature of the vapors after passing from the vaporizing zone to the requirements of the reaction by a system of heat exchange, compressing all the vapors and releasing the pressure after compression for their sudden expansion.

26. The herein-described cracking process for the production of lower boiling hydrocarbons which consists of vaporizing the hydrocarbon mass at about atmospheric pressure, and regulating the heat during the vaporizing period so as to maintain a continuous evolution of vapors, increasing and maintaining the temperature of the vapors evolved during the vaporization to a degree most favorable to the cracking operation, compressing all the vapors, and suddenly releasing the pressure after compression for the expansion of the vapors to form a resulting product of different specific gravity and boiling points to the hydrocarbon vaporized.

27. The herein-described cracking process for the production of lower boiling hydrocarbons which consists of vaporizing the hydrocarbon mass at about atmospheric pressure, regulating the temperature of the vapors after passing from the vaporizing zone to the requirements of the reaction, and compressing all the vapors and suddenly releasing the pressure after compression for their expansion.

28. The herein-described cracking process for the production of lower boiling hydrocarbons which consists of vaporizing the hydrocarbon mass at about atmospheric pressure, regulating the temperature of the vapors after passing from the vaporizing zone to the requirements of the reaction by a system of heat exchange, compressing all the vapors and releasing the pressure after compression for their sudden expansion.

29. The herein-described cracking process for the production of lower boiling hydrocarbons which consists of vaporizing the hydrocarbon mass at about atmospheric pressure, superheating the vapors of the low boiling fractions after passing from the vaporizing zone, compressing all the vapors evolved during the vaporization under controllable conditions of temperature and pressure and releasing the pressure after compression for the sudden expansion of the vapors.

30. The herein-described cracking process for the production of lower boiling hydrocarbons which consists of vaporizing the hydrocarbon mass at about atmospheric pressure, and after vaporization increasing the temperature of the vapors of the low boiling fractions to a degree favorable to the reaction, compressing all the vapors, and releas-

ing the pressure after compression for the sudden expansion of the vapors.

31. The herein-described cracking process for the production of lower boiling hydrocarbons which consists of vaporizing the hydrocarbon mass at about atmospheric pressure, compressing all the vapors on passing from the vaporizing zone under regulable conditions of pressure, releasing the pressure after compression for their sudden expansion and liquefaction, and collecting the liquefied products of all the vapors in the same receiver.

32. The herein-described cracking process for the production of lower boiling hydrocarbons which consists of vaporizing the hydrocarbon mass at about atmospheric pressure, superheating the vapors of the low boiling fractions after passing from the vaporizing zone, compressing all the vapors evolved during the vaporization under controllable conditions of temperature and pressure and releasing the pressure after compression for the sudden expansion and liquefaction of the vapors, and collecting all the liquefied products in a common receptacle.

33. A cracking process for the production of lower boiling liquid hydrocarbons which consists in vaporizing liquid hydrocarbon, transferring all the evolved vapors from the vaporizing zone to a separate pressure zone, heating the transferred vapors at will to a degree favorable to the alteration, and compressing all the evolved vapors in said separate pressure zone.

34. A cracking process for the production of lower boiling liquid hydrocarbons which consists in vaporizing liquid hydrocarbon, transferring all the evolved vapors from the vaporizing zone to a separate pressure zone, heating the transferred vapors at will during the pressure period to a degree favorable to the alteration, and compressing all the transferred vapors in said separate pressure zone.

35. A cracking process for the production of lower boiling liquid hydrocarbons which consists in vaporizing liquid hydrocarbon, transferring all the evolved vapors from the vaporizing zone to a separate pressure zone and heating the vapors at will before and during the compression to a degree favorable to the alteration, and compressing all the evolved vapors in said separate pressure zone.

36. A cracking process for the production of lower boiling liquid hydrocarbons which consists of vaporizing liquid hydrocarbon, transferring all the evolved vapors from the vaporizing zone to a separate pressure zone, compressing all the transferred vapors in said separate pressure zone under controllable conditions of pressure, and releasing the compression for sudden expansion of the compressed vapors.

37. A cracking process for the production of lower boiling liquid hydrocarbons which consists of vaporizing liquid hydrocarbon, transferring all the evolved vapors from the vaporizing zone to a separate pressure zone, compressing all the transferred vapors in said separate pressure zone under controllable conditions of temperature and pressure, and releasing the compression for sudden expansion of the compressed vapors. 20
38. A cracking process for the production of lower boiling liquid hydrocarbons which consists of vaporizing liquid hydrocarbon, transferring all the vapors from the vaporizing zone to a separate pressure zone, compressing all the transferred vapors in said 25
- 15
39. A cracking process for the production of lower boiling liquid hydrocarbons which consists of vaporizing liquid hydrocarbon, transferring all the vapors to a separate pressure zone, regulating the temperature of the transferred vapors at will to the requirements of the reaction, compressing all the transferred vapors in said separate pressure zone, and releasing the pressure after compression for their sudden expansion. 25
